DESIGN FOR A DRAPERY TIEBACK

Edward Herman, Los Angeles, Calif., assignor to George E. Bernstein, Los Angeles, Calif.

Application April 4, 1944, Serial No. 113,134

Term of patent 3½ years

(Cl. D21—1)

To all whom it may concern:

Be it known that I, Edward Herman, a citizen of the United States, residing at Los Angeles, in the county of Los Angeles and State of California, have invented a new, original, and ornamental Design for Drapery Tiebacks, of which the following is a specification, reference being had to the accompanying drawing, forming part thereof.

I claim:

The ornamental design for a drapery tieback, as shown.

EDWARD HERMAN.
